CONFECTION FORMING MOLD

Ben E. Rasmusson, 12510 SE. 62nd Place,
Bellevue, Wash. 98004

Filed Nov. 13, 1967, Ser. No. 9,369

Term of patent 14 years

(Cl. D44—1)

Fig. 1.

Fig. 2.

Fig. 4.

Fig. 3.

FIG. 1 is an isometric view of a confection forming mold showing my new design;

FIG. 2 is a rear elevational view of the confection forming mold shown in FIG. 1;

FIG. 3 is an end elevational view thereof as seen from the left of FIG. 1, the end opposite thereto being a mirror image thereof; and

FIG. 4 is a bottom plan view thereof.

This application is a continuation-in-part of design application Serial No. 4,869, filed November 30, 1966, now abandoned.

I claim:

The ornamental design for a confection forming mold, substantially as shown and described.
